UNITED STATES PATENT OFFICE.

HENRY M. PIERSON, OF BROOKLYN, NEW YORK.

PROCESS OF AND APPARATUS FOR MANUFACTURING GAS.

SPECIFICATION forming part of Letters Patent No. 279,010, dated June 5, 1883.
Application filed February 26, 1883. (No model.)

To all whom it may concern:

Be it known that I, HENRY M. PIERSON, of Brooklyn, in the county of Kings and State of New York, have invented an Improvement 5 in Processes of and Apparatus for Manufacturing Gas, of which the following is a specification.

Apparatus for making illuminating and non-illuminating gases have been constructed in 10 which steam in a heated condition, either alone or commingled with hydrocarbon vapors, have been passed up through an incandescent bed of fuel, or else down through the same, to fix or combine the gases, and in some instances the 15 steam has been highly heated before coming into contact with such carbon.

Reference is hereby made to the Low patents, Nos. 130,383 and 167,847; to Strong, No. 197,062; the H. M. and J. S. Pierson patent, 20 No. 269,162, and the Frost patent, No. 226,397, for apparatus that may be regarded as types of the general kinds of gas-making to which my improvements are available. In these modes of making gas it has been necessary to employ 25 anthracite coal exclusively, or nearly so. Otherwise two sources of difficulty arise. The first is that the coal melts and becomes so adhesive that the air will not pass freely through the same, neither will the superheated steam or 30 gases. Besides this, the soft coal does not descend by gravity, even if the retorts are opened and the fuel sliced down from the top or raked from the bottom. So, hence, it is nearly impossible to cause the fuel to settle, and gas 35 cannot be practically produced.

My invention is for the purpose of allowing bituminous coal to be made use of in gas-making apparatus of the general character before mentioned; and it consists in combining with 40 the generator or chamber containing the incandescent bed of fuel, a coker that is constructed in such a manner that the charge can be introduced in small quantities and the gases passed off therefrom and employed in heating 45 up the apparatus and in making illuminating or heating gas, and then, after the soft coal has become coked, the same is passed directly into the generator, and is better adapted to form the incandescent bed of fuel for the gas-generator than the anthracite coal employed in the apparatus before named.

In the drawings, Figure 1 is a plan view,

Fig. 2 is a vertical section at the line *x x*, and Fig. 3 is a partial section at the line *y y*.

For convenience of illustration, it is to be presumed that A is the generator, C the decomposer, and F the superheater, corresponding generally with the same similarly-marked devices in the Patent No. 269,162, and a reference is hereby made to said patent for a more detailed description of these parts and their mode of operation.

The chamber E, Fig. 3, corresponds generally with the superheater E in said patent, and the chamber B to the commingler B in said patent. In my improvement I make use of one or more sets of cokers. I have shown two sets of cokers marked, respectively, L and M; but as they are both alike I will only describe the same as if there were but one.

It is preferable to divide the coker into four chambers, 11 12 13 14, the same being formed of fire-brick clay, cast-iron, or other suitable material. There is a front plate, *s*, and a movable gas-tight cover to each coking-chamber, and descending flues at the end adjacent to the front plate, as at 16; and I prefer to have a horizontal flue, 17, beneath each of the lower chambers, 13 14. The coking-chambers are enveloped in a suitable wrought-iron case, which retains the heat and keeps the parts in their proper places.

In starting the apparatus it is preferable to introduce coke or anthracite coal in the generator A and in the decomposer C, if the same is used, and to fire up in the manner set forth in said Patent No. 269,162, allowing the products of combustion to pass off by the escape-flue D. After the fire has been kindled a charge of bituminous coal is introduced into one of the chambers—say the chamber 11—and the heating is then continued, and a supply of atmospheric air admitted at 7 causes the gases evolved to burn and aid in heating the superheaters E F. The valve *h* is then closed, the supply of air shut off, and steam is admitted at *k*, which becomes highly superheated in F and E, and passes through the coker, carrying with it gases that are evolved. These descend through the fire in the decomposer C, thence they pass through the commingler B, and at this place petroleum or other liquid hydrocarbon is added by the pipe *n*, if it is desired to make illuminating-gas; but if non-luminous

gas is being made such petroleum is not required. The gases then pass through the second coker B and the generator A, and are taken away by the pipe 7. It is, however, to be understood that the places at which the steam and the oil are supplied will vary according to the character of the apparatus to which this improvement is applied. These operations are repeated as soon as the apparatus becomes too low in temperature—that is to say, a supply of soft coal is next introduced in the coker 12 and air admitted and the valve h opened to heat up the apparatus, after which the valve h is closed, the air-supply shut off, and the gas-making resumed. The next and fourth time the apparatus requires reheating, the supply of bituminous coal is inserted into the chambers 13 and 14, respectively; and the fifth time the apparatus requires to be heated, the coke is pushed back out of the chamber 11 and a fresh supply of bituminous coal inserted; and so on in succession each chamber is discharged of coke and charged with soft coal. The coke falls into the generator or decomposer, as the case may be, and forms the incandescent bed of fuel for the steam or gases to pass up or down through the same, as the case may be, in making non-luminous or illuminating gases, according to the mode in which the apparatus is worked.

I remark that I prefer to use four chambers in each coker, but two, three, or more may be used. It is preferable to use more than one, or else the fuel will not have sufficient time for coking.

Any suitable scoop may be used for introducing the soft coal into the coking-chambers similar to that employed in gas-retorts, and I remark that it is preferable to employ a damper or plate of iron introduced into the chamber to cover the flue-opening 16 before the coal is inserted, to prevent the fuel falling into such flue; but the flue may go off at the side, if desired, so as to dispense with the opening in the bottom of the chamber.

In cases where this improvement is applied to such retorts as are used in the Low, the Frost, or the Strong patents, before referred to, the operation of the coking-chambers will be the same as before set forth; but the directions in which the steam and gases travel and the places where the steam and air are introduced will vary. Under all circumstances the coking operation will be performed in the chambers, so that when the coke is passed into the generator or decomposer such coke will become part of the bed of incandescent fuel,

and it will burn away gradually and will not adhere or clog in the vertical generator or chamber, and the coke itself, being very porous, will act upon the steam and gases to decompose the steam and fix the gases as efficiently, if not more so, than the anthracite coal heretofore employed.

In cases where this improvement is used in an apparatus that is not kept in constant operation the coking operation will stop when the gas-making is suspended, and the coking will be resumed when the blast is applied to intensify the fire.

I claim as my invention—

1. The method herein specified of manufacturing gas with soft coal, consisting in supplying the soft coal periodically and successively into separate coking-chambers, delivering the coke progressively in a state of incandescence upon a bed of incandescent coke, causing air to pass through such incandescent coke for promoting combustion and heating up the apparatus, and then passing superheated steam through the coking-retort, and the gases from the coal and the steam through the bed of incandescent coke for the manufacture of gas after the atmosphere has been excluded, substantially as specified.

2. The combination, in a gas-making apparatus, of a generator or chamber for incandescent fuel, a superheater, one or more separate coking-chambers, forming a means of communication between the superheating-chamber and generator pipes and cocks for supplying steam through the superheater and coking-chamber and incandescent coke in gas-making, and for admitting air in heating up the apparatus when the gas-making is suspended, substantially as set forth.

3. The method herein specified of manufacturing gas, consisting in supplying soft coal periodically and successively into retorts, coking the soft coal by heat from an incandescent bed of fuel, burning the gases evolved from the coal within the gas-making apparatus to heat the same, and adding the coke periodically to the bed of incandescent fuel, and causing the superheated steam to pass through the coking-retort, and the steam and gases to pass through such incandescent bed of coke to fix the same, substantially as set forth.

Signed by me this 23d day of February, A. D. 1883.

H. M. PIERSON.
